UNITED STATES PATENT OFFICE.

RAYMOND G. BRISBINE, OF DORMONT, PENNSYLVANIA.

FLOUR SACK AND LIKE ARTICLE.

1,403,287.

Specification of Letters Patent. Patented Jan. 10, 1922.

Application filed July 7, 1921. Serial No. 482,951.

To all whom it may concern:

Be it known that I, RAYMOND G. BRISBINE, residing at Dormont, in the county of Allegheny and State of Pennsylvania, a citizen of the United States, have invented or discovered certain new and useful Improvements in Flour Sacks and like Articles, of which improvements the following is a specification.

10 My invention relates to improvements in flour sacks and like articles; it is applicable to sacks for containing all sorts of commodities, but its advantages are particularly available when it is applied to sacks for containing articles of food, such as flour, meal, and the like.

20 In the accompanying drawings a sack is illustrated having my invention embodied in it. Fig. I is a view in elevation of the sack when turned wrong side out and ready for use as an apron; Fig. II is a similar view of the sack when turned right side out and ready for use as a sack; Fig. III is a view in vertical section, on the line III—III, Fig. 25 I; Fig. IV is a view in vertical section, on the line IV—IV, Fig. II; Fig. V is a view in transverse section, on the line V—V, Fig. I; Fig. VI is a view in transverse section, on the line VI—VI, Fig. II; Fig. VII shows 30 diagrammatically and in three views the article with the flap of the sack or apron cut to the pattern shown in Figures I to VI; and Figs. VIII, IX, X and XI similarly illustrate obvious variations in the pattern.

35 It is a common thing, for a housewife to use an empty flour sack in lieu of an apron. My invention consists in so constructing the sack that when in normal use, it has served its purpose as a sack, it will be serviceable, 40 not merely in lieu of an apron, but as an apron indeed.

45 Referring to the drawings, the sack is shown to be made as is usual of a single piece of material of general rectangular form, folded upon itself and stitched along two edges, as indicated at *a* and *b*. The edge *c* remains unstitched and forms the mouth of the sack.

50 According to my invention the piece of material, cut in other respects to usual shape, is provided with an extension 1, advantageously of the shape and relative size indicated in Fig. I, and extending beyond the edge, where the bottom seam *a* of the sack

is run. This extension 1 forms a flap which, 55 when the sack has been formed, extends from the bottom seam, inside the sack (cf. Fig. II), and which so arranged constitutes to the limit of its extent a second thickness of material in the wall of the sack, and so 60 adds to the strength and durability of the sack when in service.

When the sack has been emptied it may be turned wrong side out and, being then inverted, the sack with its flap assumes, as Fig. 65 I shows, the form of an apron; the flap 1 forms the bib of the apron, and the sack proper forms the body portion 2 of the apron. If desired one thickness of the otherwise double body portion may be cut away. 70

The refinements shown in the drawings though not essential, may be found advantageous. The edge of the flap 1 which ultimately forms the bib portion of the apron may be hemmed, as indicated at 3; a loop 4 75 to pass around the neck of the wearer may be added; strings 5 may be provided, secured at proper points. All these added details will, as is apparent, so long as the sack is used in its normal and intended manner, 80 lie within. When the sack being emptied is turned wrong side out, all these parts are ready, that the article may then be used as an apron.

The flap 1 may be decorated as one will, 85 or may carry advertising matter printed or otherwise applied upon it.

Fig. VII illustrates diagrammatically how the material is cut and folded to form the sack as illustrated in Figs. I-VI; Figs. 90 VIII-X illustrate variations. These diagrams explain themselves in the main. The apron of Fig. VIII is available as an apron of double thickness throughout. The apron of Fig. IX is of double length. The sack 95 of Fig. X may be made into two aprons. The apron of Fig. XI is as wide as the sack is long and twice as long as the sack is wide. These and such like variations are permissible, without departing from the spirit of 100 my invention.

The material will be such as is used for sacks, either woven fabric (commonly cotton) or paper.

I claim as my invention:

1. A sack formed of flexible material, and having an apron-bib flap extending therefrom interiorly thereof, and adapted when

the sack is turned wrong side out to constitute, together with the body of the sack, an apron.

2. A sack formed of flexible material and having formed integrally with the body thereof a flap normally extending from the bottom seam of the sack and reinforcing the sack over areas adjacent the said seam and adapted when the sack is turned inside out

to form the bib of an apron of which the sack itself constitutes the main or body portion.

In testimony whereof I have hereunto set my hand.

RAYMOND G. BRISBINE.

Witness:

FRANCIS J. TOMASSON.
